US00D726312S

(12) **United States Design Patent**
Johnson

(10) **Patent No.:** **US D726,312 S**
(45) **Date of Patent:** **** Apr. 7, 2015**

(54) **NASAL DILATOR DEVICE**(71) Applicant: **ASAP Breatheassist Pty Ltd.,**
Melbourne, Victoria (AU)(72) Inventor: **Michael Ralph Burgess Johnson,**
Hawthorn (AU)(73) Assignee: **ASAP Breatheassist Pty Ltd,**
Melbourne, Victoria (AU)(**) Term: **14 Years**(21) Appl. No.: **29/461,217**(22) Filed: **Jul. 19, 2013**(30) **Foreign Application Priority Data**

Jan. 21, 2013 (AU) 10288/2013

Primary Examiner — Bridget L Eland*(74) Attorney, Agent, or Firm* — Pillsbury Winthrop Shaw Pittman, LLP(57) **CLAIM**

The ornamental design for a nasal dilator device, as shown and described.

DESCRIPTION

FIG. 1 is a right side elevation view of a nasal dilator device showing my new design;

FIG. 2 is left side elevation view;

FIG. 3 is a rear elevation view;

FIG. 4 is a right side isometric perspective view;

FIG. 5 is a left side isometric perspective view;

FIG. 6 is a front elevation view;

FIG. 7 is bottom plan view; and,

FIG. 8 is a top plan view.
